UNITED STATES PATENT OFFICE.

EDGAR E. GREVE, OF BELLEVUE, PENNSYLVANIA.

C LINK.

Application filed January 27, 1927. Serial No. 163,981.

My invention relates to improvements in links, and more particularly to a new and improved C-link or disconnecting link employed in connection with oil well apparatus. Links of the character specified are most generally employed in connection with apparatus for pumping wells and are utilized for connecting the clevises attached to the ends of pull rods or where one clevis is attached to a pull rod and the other to a band wheel eccentric. These links are relatively heavy and, as heretofore constructed, in placing them in operative positions or attaching them to the parts as specified above, numerous accidents to operators have been met with.

The prime object of the present invention is to provide a link of the type mentioned of such construction as to reduce or practically eliminate accidents to operators in applying links in the desired operative positions.

In the accompanying drawings, which illustrate several embodiments of my invention:

Fig. 1 is a diagrammatic view of a pumping power and a pumping jack equipment showing my invention applied thereto;

Fig. 2, an elevational view of a C-link embodying my invention, showing the link applied to two clevis members;

Fig. 3, a bottom plan view of the form of Fig. 2;

Figs. 4 and 5, elevational and plan views respectively of a modified form of link; and

Fig. 6, an elevational view of a link having another modified form of handle.

In Fig. 1 of the drawings, I have shown my invention used in connection with a pumping power mechanism and a pumping jack mechanism, the C-link embodying the present invention being shown connecting two clevises, one clevis being connected with a pull rod of the jack mechanism and the other to an eccentric of the mechanism.

Referring to the drawings, the power mechanism as illustrated includes a band wheel 5 mounted on a shaft 6 and eccentrics 7 and 8, the lower eccentric 8 being the one in connection with which the C-link is employed. Projecting from the eccentric is an eccentric strap 9 and an eccentric strap clevis 10, said clevis being secured to its strap 9 by a pin 11. 12 designates a clamp connection including a link 13 secured to the clevis 10.

The pumping jack mechanism, as shown, comprises a supporting post 14, a walking beam 15, pitman 16 connected at one end to the walking beam and at its other end to the jack 17 by means of a pitman shoe box 18. Jack 17 is movably mounted on a saddle 19 and is designed to be actuated by a pull rod 20 connected to the jack by means of a clamp connection 21 and a stirrup box construction 22. 23 designates a clamp connection at the opposite end of the pull rod 20. 24 represents a polish rod of an oil well pump, adjustably secured to an end of the walking beam.

My invention contemplates to construction of a link of the character specified having means thereon that will enable the link to be applied to the parts as illustrated, or to similar parts, without the necessity of an operator grasping the link or hook portion proper, and thereby subjecting himself to injury when coupling or linking the parts. 25 designates the C-link body having hook end portions 26 and 27, a projecting member or handle preferably located on the body intermediate the hook portions thereof.

In the drawings, I have shown this handle 27 in several modified forms. In the form of Fig. 2, the handle includes a shank portion *a* of materially less cross sectional area than the hook body projecting outwardly from the body and disposed in the plane of the body, and an elongated knob or portion *b* also of materially less cross sectional area than the hook body projecting at right angles from the portion *a*, with the portion *b*, however, lying in the plane of the body.

In the form of Fig. 4, the portion *a'*, corresponding with the portion *a* of the form of Fig. 2, is similarly disposed relatively to the body as in Fig. 2, but the portion *b'* thereof is disposed at right angles to the plane of the body instead of being in the plane of the body as in Fig. 2.

Fig. 6 shows a rounded knob or portion *b* on its part *a*, in place of the elongated knob or portions *b* and *b'* of the said forms of Figs. 2 and 4.

In all of the forms illustrated, I have provided a simple and efficient handle construction that may be grasped by an operator when positioning the C-link, and the link be placed in position without injury to the operator.

What I claim is:

1. A C-link having a handle projecting

from the link body and of less cross sectional area than the link body, said handle having a knob on its outer end and disposed in the plane of the body.

- 5 2. A **C**-link having a handle projecting from the link body and of less cross sectional area than the link body, said handle having an elongated knob, said handle and its knob disposed in the plane of the body.
- 10 3. A **C**-link having an outwardly extending shank member formed integral with the link body of less cross sectional area than the link body and disposed in the plane of the body.
- 15 4. A **C**-link having an outwardly extend-

ing shank of less cross sectional area than the link body formed with a knob, said shank being formed integral with the link body.

- 5. A **C**-link having a body portion and a ²⁰ T-shaped handle of materially less cross sectional area than the body portion, the shank of the handle extending directly from the body, whereby the remaining portions of the handle will afford grips on each side of ²⁵ the shank in terminally spaced relation from the body.

In testimony whereof I affix my signature.

EDGAR E. GREVE.
